GEORGE P. ADAMSON, OF HUNTINGTON, NEW YORK, ASSIGNOR TO GENERAL CHEMICAL COMPANY, OF NEW YORK, N. Y., A CORPORATION OF NEW YORK.

PROCESS OF MAKING ALKYL SULFURIC ACID.

1,399,238.

Specification of Letters Patent.

Patented Dec. 6, 1921.

Application filed June 29, 1920. Serial No. 392,734.

To all whom it may concern:

Be it known that I, GEORGE P. ADAMSON, a citizen of the United States, and resident of Huntington, Suffolk county, New York, have invented a certain new and useful Process of Making Alkyl Sulfuric Acid, of which the following is a specification.

The invention relates to the production of alkyl sulfuric acid (and in the first instance methyl sulfuric acid and ethyl sulfuric acid) and its object is to enable the production thereof to be carried out on simple, economical and efficient lines by means of which the many disadvantageous results of the known methods of combining such alkyl alcohol and sulfur trioxid may be avoided.

Various processes have been suggested for the production of alkyl sulfuric acid from an alkyl alcohol and sulfuric anhydrid, the latter being supplied or added to a given volume of alkyl alcohol either in the form of a gas or in the form of fuming sulfuric acid. When the sulfuric anhydrid is added as fuming sulfuric acid the anhydrid is in solution in sulfuric acid, and consequently a considerable amount of sulfuric acid remains in the product. On the other hand the direct reaction between an alkyl alcohol and sulfuric anhydrid gas is difficult to control and tends to cause erratic variations of temperature resulting in the loss of alcohol as vapor. Even the use of a very low temperature does not prevent the loss of alcohol. It has been proposed to use carbon tetrachlorid as an inert diluent in which the reaction may take place, but the economical operation of this process necessitates the removal and recovery of the carbon tetrachlorid from the product obtained.

In my new process the reaction between the alkyl alcohol and sulfuric anhydrid is easily controlled and erratic fluctuations of temperature are avoided. The quality of the product may be maintained as a constant within narrow limits. No inert material is introduced which must later be removed from the product, nor is there present a large amount of sulfuric acid as is the case when the alcohol reacts with fuming sulfuric acid. The temperature at which the reaction takes place is easily maintained and there is substantially no loss of alcohol as vapor, while the sulfuric anhydrid is almost completely absorbed in the bath. The whole process runs smoothly and re-

quires little supervision. I have discovered that all of these various advantages may be secured and the numerous disadvantages of other processes overcome provided the alkyl alcohol and the sulfuric anhydrid are not brought together directly but the alcohol introduced simultaneously or successively with the sulfuric anhydrid into a bath or dominant body of the corresponding alkyl sulfuric acid which it is desired to produce, the rate of introduction of the alcohol and sulfuric anhydrid being appropriately regulated and suitable temperature conditions maintained in the bath.

The following description of one specific method which I have used successfully for making methyl sulfuric acid illustrates the principles of my invention, but I wish to be understood as not limiting myself to the details described, for these can be variously changed without departing from the invention.

The accompanying drawing illustrates diagrammatically apparatus adapted for the carrying out of the invention.

In starting this process a suitable vessel *a* is made to contain a given quantity of methyl sulfuric acid. Into the methyl sulfuric acid in the reaction vessel *a* are introduced simultaneously, and in the proper proportions for combining, methyl alcohol (through pipe *b*) and so-called contact gas (sulfuric anhydrid manufactured by the contact process and containing about 8% SO_3) through pipe *c*. The vessel *a* is, of course, suitably lined with proper brick work *d* and is provided with the exhaust *m*. The methyl alcohol is introduced into the bath through an inlet near the bottom of the reaction vessel *a*, and the contact gas is forced in through a number of small openings *e* above the alcohol inlet and rises in the liquid. These openings are shown as drilled at the top, bottom and sides of the conduit for the contact gas which is suitably supported in saddles *n*. The liquid is cooled by means of water circulating through it in coils *f* so that the temperature is kept below 150° F. preferably at 100° F., any required regulation being indicated by the thermometer *k*. The specific gravity of the product, when the operation is properly conducted, should be 1.5, and may be observed by means of a hydrometer *p* floating in the liquid in the overflow pipe *g* and covered by a glass

jar. The methyl sulfuric acid flows from the apparatus through outlet pipe *i* preferably on its top surface. The vessel *a* is provided with a glass sight hole and the glass beaker *o* serves to permit a light bulb to illuminate the interior of the apparatus so as to render the interior of the container visible. In case the specific gravity of the overflowing product falls below or rises above 1.5, this specific gravity is obtained by adjusting the rate of introduction of the sulfuric anhydrid, or of the methyl alcohol or of both. The gas escaping from the reaction vessel should be colorless, as a white fume indicates an excess of alcohol or of sulfuric anhydrid. Methyl sulfuric acid which I obtained by this process contained about 8.5 per cent. free sulfuric acid, and was suitable for one of its common industrial uses, namely, the production of dimethyl sulfate.

Ethyl sulfuric acid is manufactured in a similar manner, using a bath of ethyl sulfuric acid into which are introduced ethyl alcohol and contact gas. The specific gravity of the product is maintained at about 1.3. The ethyl sulfuric acid obtained may contain as much as twelve per cent. of free sulfuric acid and thirteen per cent. of ethyl sulfate.

The details of the process described may be varied if desired, as for instance, by using pure sulfuric anhydrid in place of the so-called contact gas, or, instead of adding the sulfuric anhydrid and alkyl alcohol simultaneously, an excess of sulfuric anhydrid may be added, then sufficient alkyl alcohol run in to combine with such excess, and the desired amount of alkyl sulfuric acid obtained by successive additions of sulfuric anhydrid and alkyl alcohol. This latter variation of my process is preferable to that wherein a large excess of alcohol is first added and the sulfuric anhydrid then introduced, as in this case the absorption of the sulfuric anhydrid may be incomplete and alcohol may be lost as vapor.

In starting the process the first step is to set up the bath or dominant body of the alkyl sulfuric acid of the desired ultimate constitution for the regular production of further quantities of such alkyl sulfuric acid. In case a supply of this material is not at hand available for the filling of the reaction vessel the following method may be pursued.

A small amount of methyl sulfuric acid is first made by passing sulfuric anhydrid into methyl alcohol at a low temperature, for example, 25° F. A large percentage of the alcohol is lost at the start, but the absorption becomes better as methyl sulfuric acid is formed. To the methyl sulfuric acid thus formed small equivalent amounts of methyl alcohol and sulfuric anhydrid are added

successively until sufficient methyl sulfuric acid has been made to start the process.

The invention is capable of being carried out in many different forms of apparatus and may be modified in so many particulars of detailed execution that I desire to make it clear that the invention is claimed broadly in such a way as to include the use of the many different possible forms of apparatus or of variation in detail; but whenever in my claims I make mention specifically of methyl alcohol or methyl sulfuric acid I intend such claims to be understood as including ethyl alcohol and ethyl sulfuric acid.

What I claim is:

1. The process of making alkyl sulfuric acid which comprises establishing a dominant bath of the desired alkyl sulfuric acid, introducing to said bath alkyl alcohol, introducing sulfuric anhydrid, and withdrawing a part of the alkyl sulfuric acid while retaining a sufficient volume thereof to constitute a dominant bath within which to continue the described process.

2. The process of making alkyl sulfuric acid which comprises establishing a dominant bath of the desired alkyl sulfuric acid, introducing to said bath alkyl alcohol, introducing a contact gas, being a gas containing about 8% of sulfuric anhydrid, and withdrawing a part of the alkyl sulfuric acid while retaining a sufficient volume thereof to constitute a dominant bath within which to continue the described process.

3. The process of making alkyl sulfuric acid which comprises establishing a dominant bath of the desired alkyl sulfuric acid, introducing to said bath alkyl alcohol, introducing sulfuric anhydrid, the alcohol and sulfuric anhydrid being supplied in combining proportions with regard to the constitution of the bath, and withdrawing a part of the alkyl sulfuric acid while retaining a sufficient volume thereof to constitute a dominant bath within which to continue the described process.

4. The process of making alkyl sulfuric acid which comprises establishing a dominant bath of the desired alkyl sulfuric acid and then introducing to said bath alkyl alcohol and sulfuric anhydrid, causing the introduced material to combine in said bath and maintaining the temperature of the bath at approximately 100-150° F. more or less.

5. The process of making alkyl sulfuric acid which comprises establishing a dominant bath of the desired alkyl sulfuric acid and then continuously introducing to said bath, alkyl alcohol and sulfuric anhydrid, cooling the bath and maintaining its temperature at less than the natural reaction temperature of the introduced material and continuously drawing off the product.

6. The process of making methyl sulfuric acid which consists in establishing a domi-

nant bath of methyl sulfuric acid and then introducing to said bath methyl alcohol and sulfuric anhydrid, causing the introduced material to combine to methyl sulfuric acid 5 in said bath and maintaining the temperature of the bath at approximately 100-150° F. more or less.

7. The process of making methyl sulfuric acid which consists in establishing a dominant bath of methyl sulfuric acid cooling said bath and then continuously introducing to said bath, methyl alcohol and sulfuric anhydrid, continuously drawing off the product and maintaining the specific gravity 10 of the product as withdrawn at a predetermined point by regulating the supply of incoming methyl alcohol and sulfuric anhydrid.
8. The process of making alkyl sulfuric acid which comprises establishing a dominant bath of the desired alkyl sulfuric acid, introducing to said bath at a low level there- 15
- 20

of alkyl alcohol, introducing at a higher level in said bath a gas containing sulfuric anhydrid, and withdrawing a part of the alkyl sulfuric acid while retaining a sufficient volume thereof to constitute a dominant bath within which to continue the described process.

9. The process of making alkyl sulfuric acid which comprises establishing a dominant bath of the desired alkyl sulfuric acid, introducing to said bath at a low level thereof alkyl alcohol, introducing at a higher level in said bath and at a multiplicity of places 35 therein a gas containing sulfuric anhydrid, and withdrawing a part of the alkyl sulfuric acid while retaining a sufficient volume thereof to constitute a dominant bath within which to continue the described process. 40

In testimony whereof I have hereunto set my hand.

GEORGE P. ADAMSON.
